TOY GUN

Ferdinand D. Began, 263 Harwood St., Elyria, Ohio

Filed Jan. 19, 1965, Ser. No. 83,497

Term of patent 3½ years

(Cl. D34—15)

FIGURE 1 is a perspective view of a toy gun showing my new design in an extended operative position;

FIGURE 2 is a side elevation taken from the side opposite of FIGURE 1;

FIGURE 3 is a muzzle end view; and
FIGURE 4 is a rear end view.

The broken line showing of a projectile in FIG. 1 is for illustrative purposes only.

The characteristic feature of my design resides in the combination on a toy gun of an elongated rod-like member extending axially through each end of a cylindrical sleeve and having a rear end portion which extends upwardly in the form of a loop and terminates in an extension coaxial with the member and a hand grip portion depending rearwardly at an obtuse angle from the extension, all as shown.

I claim:

The ornamental design for a toy gun, as shown and described.
